UNITED STATES PATENT OFFICE

ABRAHAM GINSBERG, OF NEW YORK, N. Y.

DESIGN FOR A CABINET OR THE LIKE

Application filed April 14, 1933. Serial No. 47,778. Term of patent 7 years.

To all whom it may concern:

Be it known that I, ABRAHAM GINSBERG, a citizen of the United States, residing in the city, county and State of New York, have invented a new, original, and ornamental Design for a Cabinet or the like, of which the following is a specification, reference being had to the accompanying drawing, forming part thereof.

I claim:

The ornamental design for a cabinet or the like as shown and described.

ABRAHAM GINSBERG.
